UNITED STATES PATENT OFFICE.

FRANKLIN S. SMITH, OF PHILADELPHIA, PENNSYLVANIA, ASSIGNOR TO THE PRODUCTS PROTECTION CORPORATION, OF NEW YORK, N. Y., A CORPORATION OF DELAWARE.

ELECTRIC TRANSFORMER.

Application filed December 12, 1921. Serial No. 521,777.

To all whom it may concern:

Be it known that I, FRANKLIN S. SMITH, a citizen of the United States, and a resident of Philadelphia, in the county of Philadelphia and State of Pennsylvania, have invented an Improvement in Electric Transformers, of which the following is a specification.

The general object of my invention is to improve the mechanical, thermal and electrical characteristics of electric transformers,—particularly transformers in which a gas or gases are used as the insulating and cooling means.

Other and more specific objects of the invention are to provide: an improvement in the construction of the casing in which the transformer is contained; a transformer, the losses of which may be dissipated as heat rapidly and efficiently; means for accelerating the convection currents of the gas or gases within the transformer casing; a transformer in which the wires of the primary and secondary coils are not covered with an envelope of solid dielectric, such as enamel and cotton or the equivalent, as heretofore has been the usual practice; an improvement in the winding of the high voltage coil; and an improvement in the means for supporting and insulating from each other the adjacent turns of the coils of a winding.

Other objects and advantages of my invention will be pointed out in the detailed description thereof which follows or will be apparent from such description.

For the purpose of facilitating a clear understanding of the invention and in order that the practical advantages thereof may be more readily apparent, reference is made to the accompanying drawings in which an embodiment thereof is shown; but it will be understood that various changes may be made in the details of construction within the scope of the claims hereto appended without departing from the said invention.

In the drawings:

Fig. 1 is a view in elevation of an electric transformer constructed in accordance with my invention;

Fig. 2 is a vertical longitudinal sectional view of the casing, taken on the line 2—2 of Fig. 3;

Fig. 3 is a transverse sectional view of the top dome-shaped portion of the casing,

other portions of the structure being shown in top plan;

Fig. 4 is a vertical sectional view of a portion of the casing showing a detail of construction thereof;

Fig. 5 is a transverse sectional view of the transformer structure, the right and left hand portions thereof being taken along different planes, the said view looking upward from the bottom of the transformer, certain portions of the structure within the casing being shown in bottom plan and other portions thereof in transverse section; also the structure, as shown in Fig. 5, has been turned through an angle of 90°, with respect to the position shown in Fig. 1;

Fig. 6 is a view similar to Fig. 3, but with portions of the transformer structure within the casing shown in top plan view;

Fig. 7 is a view in side elevation of the plug fitted within an opening in the side of the transformer casing near the bottom thereof for supporting the connections for supplying current to or conducting current from the low voltage coils of the transformer;

Fig. 8 is an irregular longitudinal sectional view, the casing being shown in section along the line 8—8 of Fig. 5, while the interior structure is shown partly in section and partly in side elevation, as indicated by the dash and dot line 8—8;

Fig. 9 is a longitudinal sectional view of one of the high voltage terminals;

Fig. 10 is a horizontal transverse sectional view taken along the line 10—10 of Fig. 7;

Fig. 11 is a view in side elevation of the means, of solid dielectric, for supporting the high voltage coils of the transformer, the outer wires of the said coils being shown also in elevation;

Fig. 12 is a transverse sectional view of the insulating supporting means shown in Fig. 11; with one of the coils supported thereon shown in plan;

Fig. 13 is a vertical sectional view through the said coils;

Fig. 14 is a perspective view of one of the insulating elements also employed as a spacer of adjacent coils and of turns of a coil;

Fig. 15 is a view similar to that shown in Fig. 12 but showing vertically arranged insulating means intermediate portions of the

wires of the respective coils or groups of turns of the high voltage winding, which insulating means are situated intermediate the insulating supporting means;

5 Fig. 16 is a view in elevation of a portion or section of the structure shown in Fig. 15;

Fig. 17 is a vertical sectional view taken on the line 17—17 of Fig. 15 of a portion or section of the high voltage winding of 10 the transformer;

Fig. 18 is a view in side elevation of the low voltage winding or coils;

Fig. 19 is a top plan view of the same with the insulating supporting means therefor shown in section; and

15 Fig. 20 is a view in side elevation of the casing of a transformer constructed in accordance with my invention with the interior structure shown in outline and with 20 transformer coils conventionally shown.

Referring to the drawings: It will be noted that the casing comprises a cylindrical portion 1 and a dome portion 2, the latter being of less diameter than the portion 1.

25 The bottom end of the dome portion 2 extends into an opening in the upper end of the portion 1 and is secured thereto by welding or otherwise so as to form a gas tight joint. The lower portion of the casing 1 is 30 closed by means of a shell 3, the upper end of which projects into the lower end of the portion 1 of the casing and is secured thereto by welding, so as to produce a gas tight joint. The bottom shell is placed in position and welded to the casing after the transformer apparatus has been placed and secured therein. The diameter of the dome portion 2 being less than that of the portion 1 of the casing, it follows that the upper 35 end portions of the latter extend inwardly to form an annular shoulder portion 4 surrounding the lower end of the portion 2. Openings 5 are provided in the shoulder portion 4, while openings 6 are provided in the upper end part of the dome portion 2. The openings 5 and 6 are equal in number 40 and are arranged in couples vertically. The openings of each vertical couple are in communication upon the outside of the dome portion 2 through the hollow U-shaped members 8, the edges of the sides and the upper and lower ends thereof being secured to the casing, as indicated at 9, by welding or otherwise. For the purpose of strengthening the U-shaped members 8, I have provided the transverse plates 10 which are arranged longitudinally therein and the opposite edges of which are secured to the opposite sides of the said U-shaped members.

45 For a purpose to be hereinafter referred to, the dome portion 2 is provided with three radially arranged inwardly extending flanges 14.

50 The core 15 is of known construction comprising a plurality of L-shaped steel laminæ

arranged in known manner and as indicated generally in the drawings. The four groups of these laminæ are clamped adjacent their outer sides between the opposing flanges of angle irons 16 between which and the said 70 laminæ solid dielectric 17 is interposed. The angle irons are secured or clamped together by means of bolts 18 is indicated. The upper and lower end portions of these angle irons are secured by means of bolts 19 to the outer ends of bracket-like projections

20 which extend outwardly from the ring-shaped members 21, there being one of these members adjacent the bottom portion 1 of the casing and one adjacent the top portion 80 thereof. The projections 20 are arranged in pairs as is shown in Fig. 5. For the

purpose of adjusting and tightening the respective groups of laminæ constituting the core I have provided the adjustable screw threaded bolts 22 which are in screw threaded engagement with one of the projections 20 of each pair. The inner ends of these adjustable bolts 22 contact with plates 23 as indicated which are held or kept out of contact with the core laminæ by means of solid dielectric 85, as shown. The opposite side of each group of plates rests against a sheet of solid dielectric 24 which is interposed between the said respective groups and the other one of the pairs of projections 20.

25 designates ring members concentrically situated with respect to the ring members 100 21. The ring members 25 are provided with four radially extending projections 26, the outer end portions of which are bifurcated forming bifurcations 27. The bifurcations 27 are likewise provided with projections 28 which are secured to the ring members 21. The projections 28 associated with the lower ring members 25 extend downwardly while those associated with the upper one of the said ring members extend upwardly. The projections 28 are connected or secured to the ring members 21 by means of bolts 30.

30 The high voltage winding 32 of the transformer is supported upon vertically arranged bars 35 of solid dielectric which bars are arranged in pairs as indicated, and the upper and lower ends thereof are secured to the inner sides of the bifurcations 27 of the projections 26. It will be noted that these bars taper from their central portions to their opposite ends and that in consequence the number of turns of wire in each coil decreases from the center in opposite directions. The slots within the bars 35 within which the turns of wire of the respective coils 36 are situated may be formed by cutting parallel transversely arranged slots in close relation to each other, as is indicated in Fig. 8 of the drawings. Instead, however, of thus forming the slots

105 110 115 120 125 130

35 the respective groups of coils constituting

the high voltage winding may be separated by means of alternately arranged slotted spacers of solid dielectric 37, as indicated in Figs. 12, 13 and 14. It will be noted that in these Figs. the turns of the respective coils are situated in the slots 38 of the respective spacers 37, and that each group of turns is separated from the next adjacent upper and lower groups by the said spacers.

5 In the several forms of construction the wires are bare; that is, they are not encased or inclosed in a coating or envelope of solid dielectric. In the form of construction as illustrated in Figs. 12, 13 and 14, in which 10 the wires of the high voltage windings are relatively large, insulation between turns and coils is effected entirely by the gaseous dielectric and cooling medium except the relatively smaller part of the winding partially enveloped by the spacers 37 and strips 20 of solid dielectric 51.

In the construction shown in Figs. 15 to 17 the wires are relatively thin and in consequence it is deemed advisable to interpose, 25 between adjacent portions of the wires of each group of coils intermediate the successive pairs of insulating bars thin sheets 41 of solid dielectric. These sheets are perforated at frequent intervals, as indicated 30 at 42, and for the purpose of supporting the sheets vertically between the adjacent turns of wire, pins 43 of solid dielectric are employed, as shown in Figs. 15 and 16.

35 In the construction as shown in Figs. 15 to 17 inclusive the insulating horizontal partitions or sheets 45 are plane, as indicated, and each turn of wire in each group of coils is separated by a narrow strip of solid dielectric 46, as indicated.

40 In the high voltage winding the wire is wound within the spaces between adjacent insulating sheets upon the supporting bars 35 and when the said spaces are full or when the winding therein is completed the 45 wire is carried from the outside inwardly to the next space, as indicated at 50 in Figs. 15 and 16. As indicated in the said figures, the transversely and angularly extending connecting portions of wire are separated 50 from the adjacent coils by the strips 51 of solid dielectric. The ends of the high voltage winding are connected to the wires 60 which have connection with the high voltage terminals designated as a whole by the 55 reference number 61.

These terminals are fully described and claimed in my co-pending application filed March 2, 1921, Serial Number 449,212, and it is not therefore deemed necessary to repeat the description here.

60 The low voltage winding 65 of the transformer is situated inside of and is concentric with respect to the high voltage winding above described. The said low voltage

winding 65 is illustrated in enlarged detail 65 in Fig. 19 and comprises two wires of relatively larger cross section, as shown. The opposite ends of these wires are connected in known manner to the terminals 66, the inside ends of which are shown in Fig. 7. 70 The adjacent coils of the low voltage winding are held or maintained in spaced relation to each other by spacing strips or blocks 66' of solid dielectric situated at intervals as shown in Fig. 19. The outer edges of 75 these spacing strips should terminate inside the outer edges of the wires so as to allow the gas as it flows upwardly to contact freely with every part of the outer portions of said wires.

The low voltage winding is supported in spaced relation with respect to the interior portion of the transformer core upon vertically arranged insulating bars 70 which are situated intermediate the upper and 80 lower ring member 25, as is clearly indicated in Fig. 8 of the drawings, and also partially within the right angles between the adjacent legs of the said core, as indicated in Fig. 5.

85 It will be noted that gas passageways are provided between the vertically arranged insulating bars 70 and the central leg of the core of the transformer, also between the coils of the low voltage winding and the said leg of core, also that a vertical opening is provided as indicated at 71 at the center of the core of the transformer, and also that 90 gas passages are provided between the exterior of the low voltage winding, the vertical insulating bars 35, and the portions of the high voltage winding intermediate the pairs of insulating bars 35. The coils of the high voltage winding are spaced apart 95 so that convection currents of the gaseous dielectric and cooling medium may flow between said coils.

100 One of the particular objects and purposes of my invention is to provide a construction in which a gaseous dielectric and cooling medium may be used efficiently and to great advantage. To this end one of the objects has been to provide means whereby an extremely vigorous and rapid circulation of the gaseous dielectric within the casing may be effected in order to bring about or produce a more rapid dissipation of the heat which may be developed in the transformer than heretofore has been practical in so far 105 as I am aware. To accelerate the convection currents of gaseous dielectric and cooling medium I have provided the four sheets 110 80 of solid dielectric as shown in Fig. 5, the opposite edges of which contact with the interior surface of the portion 1 of the casing along lines adjacent the corners or edges of four legs of the transformer core. The presence of these sheets forms passageways in 115 120 125

termmediate the same and the subtended portions of the casing and also vertical passageways interiorly of the said sheets. The upper ends of these sheets are connected with the lower flared end of the funnel member 81 of solid dielectric, the tubular portion 82, also of solid dielectric, of which projects upwardly into the dome portion 2 of the casing and is centered by the radial flanges 14. The upper end of the funnel 82 terminates a distance below the upper end of the dome portion 2 in a plane substantially co-incident with the lower ends of the openings 6.

15 The sheets 80, the outwardly flared portion 81 of the funnel and the tubular portion 82 are so fitted with respect to the transformer that they form a flue, the function of which is to induce a draft and there- 20 by accelerate the convection currents, of the gaseous dielectric and cooling medium, through the various gas passages provided.

After the transformer and the sheets 80 and the funnel 82 are all in place the bottom shell 3 is placed in position, as indicated in Fig. 8 of the drawing, and is secured by welding. The inner upper end of the said shell contacts with the lower ends of one of the flanges of each of the angle irons 16 so that the latter are supported securely in position thereby. Prior, however, to the securing of the bottom shell in position molten lead, or other material of good thermal conductivity, is poured down into the spaces between the outwardly extending flanges of the angle irons 16, the adjacent edges of the laminæ of the four legs of the transformer and the casing. Suitable sheets of thin solid dielectric 88 are interposed between the said lead and core laminæ so as to prevent short circuiting of the latter.

40 The transformer losses are dissipated as heat, by radiation, conduction, and convection. As these three modes of heat dissipation are common to all transformers embodying a fluid cooling medium, only the means by which increased efficiencies are obtained by my invention will be further described.

50 The amount of heat radiated is strictly proportional to the nature and extent of the surfaces and is independent of the presence of the gaseous dielectric adjacent to the surfaces. This is not true in transformers embodying a liquid dielectric such as oil.

However, the greater part of heat dissipation is effected by conduction and by convection currents. By conduction through the relatively stationary gaseous film adjacent to the transformer surfaces, thence by convection currents to the gaseous film adjacent to the inner surface of the casing and then by conduction through this film.

As the greater portion of the transformer

windings are bare, that is, not enveloped by 65 solid dielectric, the thermal resistivity of the paths through which the heat must be carried by conduction, is greatly decreased.

As heretofore explained convection currents are greatly accelerated by flue action obtained by the flue composed of elements 80, 81 and 82 shown in Fig. 8 because of heat given to gas or gases in long passages.

The paths of these convection currents are as follows,—through the various gas 75 passages provided adjacent to the windings and core and within the lower part of the flue and upwards and through the open end of tubular portion 82 thence descending between the tubular portion of the funnel and the opposed inside surfaces of the dome portions 2 and other portions thereof outwardly through the openings 6 and down through the passageways provided by the U-shaped 80 parts 8. The descending flow of the gases continues through the passageways between the sheets 80 and the subtended portions of the casing 1, ultimately passing inwardly underenath the lower edges of the said sheets 80, thence again upwardly and so on continuously.

85 In Fig. 20 of the drawings I have shown diagrammatically and in dotted lines the high and low voltage coils, 86 and 87, within the casing, the connections thereof with their respective terminals, and their relation to the means for effecting circulation of the cooling medium,—which is the gaseous dielectric. Any suitable dielectric may be employed but I prefer to employ a mixture 90 of nitrogen and helium. However, nitrogen alone has been employed with very satisfactory results. The gas is employed under pressure greater than atmospheric and up to 100 about fifteen atmosphere.

Having thus described my invention, what I claim and desire to secure by Letters Patent is:

1. In a transformer structure, the combination of the transformer, means situated at intervals for supporting the high voltage winding thereof, the portions of the wire of said winding intermediate said supports being bare on all sides and spaced from each other whereby the cooling medium within the transformer casing may impinge upon all parts of the surfaces of the said portions of wire, a hermetically sealed casing for the transformer, and means associated with the transformer and within the casing for providing passageways through which there is a continuous circulation of the cooling medium upwardly adjacent to the parts of the transformer and downwardly upon the outside of the said transformer and within the said casing.

110 115 120 125 2. In a transformer structure adapted to the use of a gaseous dielectric, the combina-

- tion of a hermetically sealed exterior casing having a reduced upper end portion, a transformer within the lower portion of said casing, which casing extends a substantial 65 distance above said transformer, an interior flue within which said transformer is situated which interior flue is open at its upper and lower ends, and the upper end of which is of reduced diameter and extends a substantial 70 distance above said transformer into the reduced upper end portion of said casing, and the said interior flue being spaced from the interior of said exterior casing so as to form passageways between the said 75 casing and said flue through which currents of the said gaseous dielectric descend.
3. A transformer, including a high voltage winding composed of parallel coils, supports of solid dielectric arranged at intervals 80 for supporting said winding, the portions of wire upon said supports being separated from each other by solid dielectric, and the portions thereof intermediate said supports being bare.
- 25 4. A transformer situated within a hermetically sealed casing containing a gaseous cooling medium which transformer includes a high voltage winding of parallel coils, supports arranged at intervals for supporting 85 said coils, the portions of coils upon said supports being separated from each other by solid dielectric material and the portions thereof intermediate the said supports being separated only by the said gaseous cooling 90 medium.
- 35 5. In a transformer structure adapted to a gaseous insulating and cooling medium, the combination of a gas tight casing, a flue within said casing, the upper and lower ends 95 and sides of which are spaced from the upper and lower ends and sides of said casing whereby a passageway is formed within said casing exteriorly of said flue, and a transformer within said flue, the windings of 100 which are substantially bare.
- 40 6. In a transformer structure, the combination of a hermetically sealed casing having a dome portion at its upper end, a transformer situated within the casing a distance 105 below the said dome portion, a funnel situated above said transformer and extending into said dome portion and terminating below the top of the latter, the diameter of the tubular portion of said funnel being less 110 than the internal diameter of the said dome portion whereby a space is provided between the said tubular portion and the said dome portion, and a plurality of sheets connected at their upper ends to portions of 115 the lower flared end of the said funnel, the said sheets subtending portions of the said casing to form passageways, the lower ends of which are open and the upper ends 120 of which are in communication with the space between the exterior of the said funnel and the adjacent opposing portion of the casing.
7. In a transformer structure adapted to a gaseous cooling medium, the combination of a transformer, the wires of the windings of which are bare, a hermetically sealed casing having a dome-shaped extension at its upper end directly above the said transformer, a funnel situated above said transformer and the tubular portion of which extends into said dome-shaped extension, and means upon opposite sides of said transformer intermediate the same and adjacent portions of said casing co-operating with the latter to form passageways to direct the 125 heated gases upwardly into the said funnel which gases after escaping from the upper end of said funnel descend upon the outer side thereof and through the said passageways.
8. In a transformer structure adapted to a gaseous cooling medium, the combination of a transformer, a hermetically sealed casing surrounding said transformer and having a dome-shaped portion at its upper end of less diameter than the body portion thereof, the said body portion having a plurality of openings in its top outside the lower end of said dome-shaped portion, and the said dome-shaped portion having openings in its upper end portion and also being provided with tubular members upon its outer side, the lower end of each of which is in communication with one of the first 130 named openings and the upper end of which is in communication with one of the second named openings whereby open-ended passageways are provided on the outer side of said dome-shaped portion, a funnel situated above the transformer and supported thereon, the tubular portion of said funnel extending upwardly into the said dome-shaped portion and terminating below the upper end thereof, and the lower end of said funnel being provided with sheets which extend 135 downwardly and terminate adjacent the lower end of the casing, the said sheets co-operating with the adjacent opposing portions of said casing to form passageways, the said passageways being in open communication at their lower ends with the lower portion of the interior of said casing and communicating at their upper ends with the space between the funnel and the said casing and with the said passageway upon the outer side of the said dome-shaped portion of the casing.
9. In a transformer structure, the combination of an exterior hermetically sealed casing having a dome-shaped portion at its upper end, a transformer within the lower portion of said casing, an open-ended casing 140 within the said exterior casing and sup-

- ported upon the said transformer, the said open-ended casing being provided with a portion which projects upwardly into the said dome-shaped portion, the external diameter of said portion being less than the internal diameter of the said dome-shaped portion thereby forming a space between the said portion and passageways between lower portions of the said exterior and interior casings, which passageways are in communication at their upper ends with the space between said portions and at their lower ends with the lower portion of the interior of the said external casing.
- 10 15 20 25 30 35 40 45 50 55 60 65 70 75 80 85 90 95 100 105 110 115 120 125 130
10. In a transformer structure, the combination of a hermetically sealed exterior casing having a dome-shaped portion at its upper end, a transformer situated within and concentrically of the lower half portion of said casing, the wires constituting the winding of said transformer being bare and the respective coils and the portions of wire of each coil being separated from each other so as to provide spaces between the said coils and the said wires for the free passage of a cooling medium, an internal casing supported upon the said transformer and having a portion of less diameter than the interior diameter of the said dome-shaped portion which projects into the latter and terminates a distance below the top thereof, and also having side portions which co-operate with the portion of the said exterior casing in opposed relation to the said transformer to form passageways the lower ends of which communicate with the lower portions of the said exterior and interior casings, and the upper portions of which are in communication with the space between the dome-shaped portion of the exterior casing and the portion of the interior casing projecting into the latter.
11. In a transformer structure, the combination of a hermetically sealed casing having a dome portion at its upper end of substantially less diameter than the lower portion, a transformer situated within the said lower portion, a funnel having its tubular portion extended into said dome portion, the external diameter of said tubular portion being less than the interior diameter of said dome portion, and the lower flared end portion of said funnel being supported on said transformer, and sheets connected to the lower end of said funnel and subtending the angles between the legs of the core of said transformer and also subtending portions of the said casing to form internal and external passageways.
12. A transformer casing having a dome-shaped portion at its upper end, hollow rib-like portions secured at intervals to the outer side of the said dome-shaped portion, and the said dome-shaped portion having open- ings in its upper end in communication with the upper ends of the said rib-like portions, and the said casing having openings therethrough outside of the lower end of said dome-shaped portion which openings are in communication with the lower ends of the said hollow rib-like portions.
13. A hermetically sealed casing for electric transformers, comprising portions of different diameters the portion of smaller diameter projecting upwardly a substantial distance from the top of the portion of larger diameter, and the said smaller portion being provided with passageways exteriorly thereof, the upper ends of which communicate with the interior of the top portion thereof, and the lower ends with the top portion of the larger portion of said casing, whereby portions of the dielectric within the casing escape from the upper part of the smaller portion of said casing and descend through the said passageways to the upper part of the interior of the larger portion of said casing.
14. A transformer comprising high and low voltage windings situated in spaced relation to each other, the space between the said windings being adapted to permit the passage of a fluid cooling medium therethrough, insulating supports situated at intervals for supporting the wires of the said windings, the said supports comprising means for supporting the wires in each of the windings in separated relation with respect to each other, and the said wires being bare on all sides.
15. A transformer, including a high voltage winding, the wires of said winding being divided into groups of coils the end of the top wire of each coil being connected with the end of the bottom wire of each succeeding coil, supports arranged at intervals for supporting said winding, the portion of wire upon said supports being separated from each other by insulating material, and the portions thereof intermediate the said supports being bare on all sides whereby the cooling medium is adapted to contact with all portions of the surfaces of the wires intermediate the said supports.
16. A transformer including a high voltage winding the wires of which are divided into groups of coils, vertical insulating bars situated at intervals in radial relation to the axis of the transformer for supporting the said high voltage winding, each of the said bars being provided with insulating means for separating adjacent coils, and means for separating the adjacent wires of the respective coils, and the portions of the wires of the respective coils intermediate adjacent bars being bare on all sides.
17. A transformer, including a high voltage winding, the wires of which are divided

into groups of coils, supports of insulating material arranged at intervals for supporting the said winding, each said support comprising two bars situated in proximity to each other and insulating means carried upon each of the said bars for supporting the wires of adjacent coils, and the portions

of wire intermediate each support and between the bars of each support being bare, substantially as described. 10

In testimony that I claim the foregoing as my invention, I have hereunto signed my name this 7th day of December, A. D. 1921.

FRANKLIN S. SMITH.
